AIR BRUSH

John R. Adams, Chicago, Ill., assignor to Binks Manufacturing Company, Chicago, Ill., a corporation of Delaware

Application March 2, 1959, Serial No. 54,795

Term of patent 14 years

(Cl. D62—2)

Fig. 1

Fig. 2

Fig. 3.

Fig. 1 is a top plan view of the air brush comprising my design.

Fig. 2 is a side elevational view thereof.

Fig. 3 is a perspective view of the air brush comprising my design with the container omitted for purposes of convenience in illustrating the design.

The dominant features of my design reside in the portions shown in full lines.

I claim:

The ornamental design for an air brush, substantially as shown and described.
